UNITED STATES PATENT OFFICE.

EDWARD G. BABCOCK, OF NEW BRITAIN, CONNECTICUT, ASSIGNOR TO
CHARLES J. WHITE, OF SAME PLACE.

GARMENT-SUPPORTER.

SPECIFICATION forming part of Letters Patent No. 392,397, dated November 6, 1888.

Application filed March 30, 1888. Serial No. 268,963. (No model.)

To all whom it may concern:

Be it known that I, EDWARD G. BABCOCK, a citizen of the United States, residing at New Britain, in the county of Hartford and State 5 of Connecticut, have invented certain new and useful Improvements in Garment-Supporters, which improvements are fully set forth and described in the following specification, reference being had to the accompanying sheet 10 of drawings, in which—

Figure 1 is a front side view of a supporter embodying my improvements. Fig. 2 is an edge view of the same, and Fig. 3 is a side or edge view of a similar supporter cut away on 15 line *x x* of Fig. 1.

My invention is in that class of garment or fabric supporters which hold the fabric between spring-actuated jaws, the upper end of one member of the device being generally so 20 formed that a tape, elastic, or other form of strap may be connected to it. My purpose is to improve such supporters by providing jaws of peculiar construction and action that serve to hold the fabric firmly without the tendency 25 to tear or stretch it that exists in some of the supporters in common use. I also provide a floating pivot or fulcrum, so that when necessary the jaws may be widely opened to receive thick fabrics; and I further improve the 30 general form and construction of the plates that form the two principal members of the complete device.

Referring to the drawings, the letter *a* denotes the larger member, formed, preferably, 35 from sheet-metal stock, punched to form a blank with projecting portions at the sides and lower ends, these portions being bent at an angle to the main plate to form the pivot-earns *b b'* and the jaw *c*, as shown in the drawings.

The upper end of plate *a* is formed with an opening, *a'*, to receive a suspending-strap. The companion member *d* is also formed as a 45 plate with inturned flanges or ears *e e'* to engage the companion ears *b b'*. One end of plate *d* is bent inwardly at an acute angle relative to its main plate to form a fabric-holding jaw, *c'*, and the opposite end projects upward to provide an operating-handle or thumb-piece, *f*. The pivot-ears on one member (preferably the outer one) are perforated to receive

a rivet, *h*, while the ears on the companion member are provided with slots *i*, that are coincident with said perforations, and through which the rivet *h* also passes. A spring, *k*, 55 acting with a constant tendency to spread the upper ends of the companion plates, and thus hold the jaws in close engagement, is provided, the body of said spring being preferably coiled about rivet *h*, so that it (the spring) 60 cannot become displaced. The slots *i* in one member allow a limited longitudinal adjustment of the members relative to each other to separate or bring closer together the jaws *c c'*, so that thick fabrics or several thicknesses of 65 the same may be entered between the jaws.

I have materially improved the form and action of the holding-jaws by bending them inward at an acute angle and causing the outer face of jaw *c'* to abut the inturned end of the 70 companion jaw *c*. With this construction the end of jaw *c'* projects past the end of jaw *c* and abuts the plate *a*. When a fabric is inserted and carried upward between said jaws, it is clasped in two places—that is to say, between the end of each jaw and its engaging-plate—and supports said fabric firmly, with less liability of tearing or stretching it than when grasped in one place only. The holding power or grip of the jaws is still further 75 augmented by providing the pivot-slot in one member, as above described, for the obvious reason that any strain or pull of the fabric serves to draw down the upper jaw, *c'*, and thus grip firmer the fabric that lies between 80 its outer face and the end of the companion jaw *c*.

My complete device may be cheaply produced, and is of such simple arrangement that it may be operated without special instructions or explanation.

I am aware that a prior patent shows a clasp formed of two connected plates provided at their free ends with inwardly-inclined jaws, whose ends are even and abut directly against 95 each other. Such a clasp is hereby disclaimed.

I claim as my invention—

1. The garment-supporter herein described, formed of two connected plates, said plates being provided at their free ends with inwardly-inclined angular jaws, the end of the outer jaw extending over the outer face of the in-

ner jaw, which face abuts against said end of the outer jaw, substantially as described, and for the purpose specified.

2. A garment-supporter consisting of spring-actuated jaws, one member of said jaws being provided with oblong slots, through which the pivotal pin passes, substantially as described, and for the purpose specified.

3. In a garment-supporter, the combination of the spring-actuated plates having at their free ends acute-angular jaws, the principal

member being formed of a single piece of sheet metal with perforated end and integral jaw, and the other member being provided with oblong slots, through which the pivotal pin passes, to allow the same to be adjusted relative to the companion member, substantially as described, and for the purpose specified.

EDWARD G. BABCOCK.
